UNITED STATES PATENT OFFICE.

WILHELM SCHMIDT, OF HALBERSTADT, PRUSSIA, GERMANY.

UTILIZING EXHAUST.

SPECIFICATION forming part of Letters Patent No. 429,774, dated June 10, 1890.

Application filed November 12, 1888. Serial No. 290,588. (No model.) Patented in Germany May 9, 1885, No. 34,358; February 6, 1886, No. 36,571, and June 2, 1886, No. 37,620.

To all whom it may concern:

Be it known that I, WILHELM SCHMIDT, a subject of the King of Prussia and German Emperor, and a resident of 8 Plantagen 5 Strasse, Halberstadt, in the Kingdom of Prussia, German Empire, have invented certain new and useful Improvements in Apparatus for Utilizing Exhaust, (for which I have received patents in Germany, dated May 9, 10 1885, No. 34,358; dated February 6, 1886, No. 36,571, and dated June 2, 1886, No. 37,620,) of which the following is a complete specification, and which constitutes a combination of the invention.

15 My invention consists in passing high-pressure steam through an ejector and by means of the jet forcing low-pressure or exhaust steam into a water-reservoir or low-pressure boiler. The water in this reservoir is thereby 20 heated and converted into steam, and the steam so generated is mixed with that forced into the reservoir by the ejector. This low-pressure steam is then used for driving steam-engines.

25 By means of my invention not only is the heat in the high-pressure steam transferred to the low-pressure steam, but the volume of the same is increased.

It is essential for the proper working of my 30 invention that the steam from the ejector is not led direct into the steam-space of the reservoir or low-pressure boiler, but first through the water-space and then into the steam-space.

The high-pressure cylinder of a compound 35 engine receives its steam from a reservoir or boiler which is heated by high-pressure steam. The steam used for heating this boiler is generated in a separate high-pressure boiler, and forces steam of a lower pressure at the same 40 time into the low-pressure boiler. This low-pressure steam which the high-pressure steam forces into the reservoir is drawn off from the receiver or receivers of a compound engine, so that only a part of the steam in the receiver 45 is used for further work in the medium or low-pressure cylinders of a compound engine.

In order to make my invention more clear, I refer to the accompanying drawing, which forms part of this specification.

50 The drawing shows my invention applied to a receiver three-cylinder compound engine.

The action of my apparatus is as follows: In the arrangement shown P Q R are the three cylinders of a triple expansion engine. M M' are receivers between the high and me- 55 dium and medium and low pressure cylinder.

The working is as follows: In the high-pressure boiler steam of forty atmospheres is generated. In the low-pressure boiler N there is a pressure of fifteen atmospheres. The 60 high-pressure cylinder P is in direct communication with the low-pressure boiler N, and the steam is expanded in the cylinder P from fifteen atmospheres down to eight atmospheres, and exhausts into the receiver M, in 65 which there is a pressure of eight atmospheres. Part of this steam is used to drive the medium-pressure cylinder Q, and is here expanded from eight atmospheres down to four atmospheres, when it exhausts into the receiver M'. 70

Part of this steam is used in the low-pressure cylinder R, where it is expanded from four atmospheres down to the atmospheric pressure. The rest of steam in the receiver M' is 75 drawn off by the high-pressure ejector b³, and which is fed by pipe b² from the high-pressure boiler A, forced through the ejector b⁴, in passing through which it draws the steam from the receiver M, which was not required for the cylinder Q. The steam of forty at- 80

mospheres meeting the exhaust-steam of four atmospheres from the receiver M' gives a mixture of steam of twenty-five atmospheres, which, in passing through the ejector b⁴, meets the exhaust-steam from eight atmospheres 85 from the receiver M, giving a result of fifteen atmospheres, which is forced into the low-pressure boiler N, to be used in the high-pressure cylinder P. The low pressure serves as a governor or regulator to regulate the 90 fluctuations in the pressure and heat of the high-pressure steam, the water taking and storing up the superfluous heat from the same, and when the temperature and pressure of the high-pressure steam falls the water in 95 the boiler N gives it off again in the form of steam that it produces auxiliary steam.

Having thus fully described and ascertained the nature of my said invention, what I desire to secure by Letters Patent of the 100 United States is—

1. In apparatus for utilizing exhaust, a high-

pressure boiler in communication with a water-reservoir through two or more ejectors, the first being actuated by steam from the high-pressure boiler, the second ejector actuated by the steam from the first ejector, and so on, a high-pressure cylinder in communication with the water-reservoir, a medium-pressure cylinder, a low-pressure cylinder, a steam-receiver between the high and medium pressure cylinders, and a steam-receiver between the medium and low pressure cylinders, the receivers being connected with said cylinders and also with the ejectors situated between the high-pressure boiler and water-reservoir, substantially as and for the purpose described.

2. In apparatus for utilizing exhaust, a high-pressure boiler in communication with a water-reservoir through two or more ejectors, the first being actuated by steam from the high-pressure boiler, the second ejector actuated

by steam from the high-pressure boiler, the second ejector actuated by the steam from the first ejector, and so on, a steam-pipe coil placed in the water-reservoir through which the steam from the ejectors passes, a high-pressure cylinder in communication with the water-reservoir, a medium-pressure cylinder, a low-pressure cylinder, a steam-receiver between the high and medium pressure cylinders, and a steam-receiver between the medium and low pressure cylinders, the receivers being connected with said cylinders and also with the ejectors situated between the high-pressure boiler and water-reservoir, substantially as and for the purpose described.

In witness whereof I have hereunto set my hand in presence of two witnesses.

WILHELM SCHIMDT.
